INVENTOR

Richard S. Reynolds,
BY
J. B. Munnell.
ATTORNEY

UNITED STATES PATENT OFFICE.

RICHARD SAMUEL REYNOLDS, OF LOUISVILLE, KENTUCKY.

RECEPTACLE.

1,358,875.

Specification of Letters Patent. Patented Nov. 16, 1920.

Application filed October 21, 1918. Serial No. 258,922.

To all whom it may concern:

Be it known that I, RICHARD SAMUEL REYNOLDS, a citizen of the United States, residing in the city of Louisville, county of Jefferson, and State of Kentucky, have invented a new and useful Receptacle, of which the following is a specification.

This invention relates to receptacles constructed of fibrous material, such as paper or paste board, and an object is the provision of a receptacle, of the character described, which may be used in place of those now constructed of metal, such as tin, and used as containers for substances which are subjected to deterioration by exposure to air or moisture.

With the foregoing and other objects in view the invention consists of the novel construction and arrangement of parts illustrated in the accompanying drawing, which forms a part of this specification, wherein is set forth an embodiment of the invention, but it is to be understood that such changes and modifications may be resorted to as come within the scope of the claims appended hereunto.

In the drawing wherein similar reference characters designate like parts in the several views, Figure 1, is a plan view of a blank used in constructing an embodiment of the invention: Fig. 2, a perspective view of the blank, portions being broken away showing blocks affixed to the sections which form the bottom and the cover of the finished box: Fig. 3, a side elevation of Fig. 2: Fig. 4, a top plan view of a box partly formed: Fig. 5, a perspective view of a completed box with the cover raised: Fig. 6, a central vertical longitudinal section on an exaggerated scale: Fig. 7, a plan view of a blank with an adhesive, and a lining applied thereto and Fig. 8, a diagrammatic plan of means for applying heat and pressure to a shaped receptacle held upon a form.

The embodiment described herewith comprises a duplex walled vessel having flat sides and rounded edges, both walls, the bottom and cover of which are formed from a blank —10— (Figs. 1 and 8). The blank comprises two quadrangular sections —11— 50 which form the walls, these sections

are connected by a third section —13— which forms the bottom, the dimensions of which correspond with the cross section of the box, a fourth section —14— similar 55 in shape to the bottom section extends from one of the wall sections and forms the cover, a tab —15— extends from the cover. A block —16— is affixed to the bottom section and a block —17— to the cover, these 60 blocks are contoured in conformity with and are slightly smaller than the sections to which they are attached. The block 16 has parallel walls while the walls of the block 17, are slightly tapered to permit it to enter 65 the box when the cover is closed. The width of the wall sections is equal to the height of the box, and their length to the distance around the box, for obvious reasons 70 the section which forms the outer wall must 75 be slightly longer than the other. In forming a box, a suitable adhesive —18— is applied along the lower edge of the wall sections (see Fig. 1) as 11, which is then turned up at right angles to the bottom, as on dotted lines —19—, at its point of connection therewith, or the adhesive may be applied to the edges of the block 16. After bending up the wall section 11, the wings —20— thereof are bent to conform to the block 16 80 (see Fig. 4), to which the lower edges adhere. This operation is best performed upon a form, or mandrel of the size of the interior of the box. An adhesive is then applied to the upper surface of the other wall 85 section, which is then turned up on the dotted line —21— and the wings —22— thereof bent around the already formed section 11, to which it adheres, becoming an integral part thereof, and in conjunction therewith 90 forms a rigid wall. A receptacle constructed as described will be found serviceable in many instances, but in order to make the receptacle air and water proof, I make an adhesive which is fluent by fusion only, and 95 with which a sheet of paper may be coated and when allowed to cool, it will present a smooth hard surface, not sticky, that may be easily handled in subsequent operations. Said adhesives having the property of becoming adhesive upon the application of 100 pressure at a temperature of above 200 de-

grees, of having sufficient permanent flexibility that the walls shall not crack after aging or when dented in handling, of being impervious to air, gases and moisture, 5 and which will neither affect nor be affected by the contents of the receptacle. From a sheet, or web coated with the adhesive described, I cut a blank, such as previously described, upon this blank the blocks 16 and 10 17 are positioned and caused to adhere thereto by the application of heat and pressure. The blank is then formed up as previously described and placed upon a form or mandrel —25— (Fig. 8) and heated molds —26— 15 brought to bear against it exerting pressure upon and causing adhesion of all parts, the softened adhesive filling and hermetically sealing any and all crevices that may exist. The block on the cover is tapered so 20 that it will enter the top of the receptacle, but the base thereof is of such size that it will make an air tight fit with the walls. The cover will be firmly held by the tight fit of the blocks, but to make doubly 25 secure it may be secured by any other suitable means, as by means of a snap fastener. Snap fasteners being articles of commerce are not thought to require description, suffice to say that a stud —30— 30 is secured in the front wall of the body of the receptacle and a spring head —31— to the tab. For some purposes it may be desirable to place a lining paper as —32— (see Fig. 7) over that portion of the inner wall 35 with which the contents will come in contact.

From the foregoing description it will be recognized that I have produced a receptacle which is air, gas and moisture proof and 40 which is susceptible of replacing receptacles now made of tin, or other metals, which may be economically constructed and which will be durable in service.

Having thus described my invention so 45 that anyone skilled in the art pertaining thereto can make and use the same, I claim:

1. A box having flat sides and rounded edges, said box comprising duplex walls which will completely encircle the box, a 50 bottom and a lid all formed from an integral sheet of material.

2. A blank comprising a pair of sections adapted respectively to form the inner and outer walls of a receptacle, said sections being joined by a section contoured to serve as the bottom thereof, a section contoured to serve as the lid or cover extended from an edge wall section, blocks contoured similarly thereto secured respectively to said bottom 55 and cover sections, the block affixed to the bottom having parallel sides and that affixed to the cover having converging sides.

3. A blank comprising a plurality of integral sections adapted to form a box, one 65 of said sections having parallel sides and

rounded ends adapted to form the bottom of the box, a wall section rectangular in outline extended from one side of said bottom section, and adapted to be turned up at right angles thereto and shaped to conform therewith, another wall section extended from the other side of the bottom section and adapted to be turned up at right angles thereto and folded about the first mentioned wall entirely encircling same, and a lid section similar in shape to the bottom, extended from the free edge of a wall section. 70 75

4. A receptacle comprising a bottom having parallel sides and rounded ends, a block similarly contoured affixed to said bottom, a wall extended from one side of the bottom and shaped to conform to said block with its vertical edges abutting and its lower edge adherent to the block, a wall extended from the other side of the bottom and encircling 85 the first named wall to which it is adherent.

5. A receptacle comprising a bottom having parallel sides and rounded ends, a block similarly contoured affixed to said bottom, a wall extended from one side of the bottom 90 and shaped to conform to said block with its vertical edges abutting and its lower edge adherent to the block, a wall extended from the other side of the bottom and encircling 95 the first named wall to which it is adherent, a lid extended from the upper edge of a wall and provided on its inner face with means adapted to be frictionally engaged with the inner side of the receptacle around the opening thereinto to hold the lid closed. 100

6. A container comprising a bottom having parallel sides and rounded ends, an elevation similarly contoured positioned on said bottom a spaced distance from the edge thereof, a rectangular wall section extended 105 from a side of the bottom the width and length thereof equaling respectively the height and circumference of the box it is being shaped to conform to, the bottom with its lower edge affixed to the edge of said elevation by means of an adhesive, a rectangular wall section extended from the other side of the bottom, the dimensions of which are substantially the same as the inner section which it encircles and to which it is adherent, covering the joint between its juxtaposed edges, and a closure hingedly connected with the free edge of a wall and an elevation on the inner face thereof adapted 115 to be frictionally engaged with the inner 120 surface of the container around the mouth thereof.

7. A container comprising a bottom having parallel sides and rounded ends, an elevation similarly contoured positioned on 125 said bottom a spaced distance from the edge thereof, a rectangular wall section extended from a side of the bottom, the width and length thereof equaling respectively the height and circumference of the box, it being 130

shaped to conform to the bottom with its lower edge affixed to the edge of said elevation by means of an adhesive, a rectangular wall section extended from the other side of 5 the bottom, which is adherent to the first mentioned wall section, covering the joint between the juxtaposed edges thereof and a closure hingedly connected with the free edge of a wall and an elevation on the inner face of said closure adapted to be frictionally engaged with the inner surface of the container around the mouth thereof. 10

RICHARD SAMUEL REYNOLDS.
